[57] CLAIM

The ornamental design for a bead puzzle, substantially as shown and described.

DESCRIPTION

FIG. 1 is a side elevational view of a bead puzzle showing my new design;

FIG. 2 is a top plan view thereof;

FIG. 3 is another top plan view thereof with the left hemisphere rotated 90°;

FIG. 4 is another top plan view thereof similar to FIG. 2, but showing the right hemisphere in an alternate position;

FIG. 5 is a top perspective view thereof; and

FIG. 6 is a bottom perspective view thereof.
